UNITED STATES PATENT OFFICE

2,260,139

PIANO

Samuel Trude Fripp, London, England

Application March 21, 1939, Serial No. 263,120
In Great Britain March 25, 1938

3 Claims. (Cl. 84—180)

This invention relates to pianos and is concerned with the provision of improved forms of music rest for instruments of either the "grand" or "upright" type.

As at present constructed the music rest of a grand piano is stored, when the piano is closed, beneath a horizontal panel or lid which is hinged to the piano top some distance from the keyboard or front of the piano and in operation this panel or lid is raised from the front. The music stand is then raised upon its hinge into position for use. In the case of upright pianos the music rest usually depends from a hinged mounting at the top of the front of the piano, the rest usually being collapsible and turnable about the hinged mounting in its collapsed state into the open top of the piano after which the lid may be closed.

The object of the present invention is to eliminate the cumbersome music rest entirely and provide an improved and novel form of piano case.

According to the invention a portion of the piano case itself is utilised as the music rest, the said portion constituting part of the top or front of the instrument in the case of grand pianos and being hingedly mounted so that it can be opened about its hinge mounting to form a music rest.

In grand pianos this portion or panel, at the front of the top of the instrument, may be hinged at its front end adjacent the keyboard so that it opens from the back and is supported in its open position at the desired angle suitably to support the music. However this arrangement has the possible disadvantage that the polished top of the panel may become scratched and according to a further feature of the invention this possible disadvantage is overcome by hingedly and slidably mounting the panel relatively to the front or the front of the top of the instrument so that it can be opened into a position in which its inner face forms the front face of the music rest.

One embodiment of the invention will now be more particularly described, by way of example, with reference to the accompanying drawing, in which:

Figures 1 and 2 are plan views of a grand piano showing a preferred construction of the top of the piano case with the panel in the closed and open positions respectively, and

Figures 3 and 4 are fragmentary sectional views on a larger scale showing the panel in its open position and in the course of being closed or opened respectively.

Referring to the accompanying drawing, the piano top is divided into a front portion or panel

10a and a lid 12a which may be opened from the side. The centre part of the panel 10a is formed as a separate panel 11a to constitute the music rest. This music rest is provided with pins or sliders 17 at its sides which slide in horizontal grooves or guides 18 bordering it. As shown, these grooves or guides are constituted by members 19 attached to the underside of the panel 10a. When the music rest is not in use the pins 17 register in recesses or notches 20 in the underside of the panel 10a forming the top member of the grooves or guides. When the music rest is required for use it is hinged upwardly about these pins 17 which are, by this action, released from the recesses or notches 20 and the music rest can then be turned up so that its inner or under face forms the front face of the rest, the music resting on a ledge 21 located at or adjacent its bottom edge. This ledge 21 is only exposed when the music rest is in position for use since in the other position it lies on the underside of the rest which fits snugly and flush, in a recess in the middle of the panel 10a as shown, with its polished surface exposed.

25 The rest is arranged to adopt the desired angle by reason of its bottom edge 22 making contact with the underside of the front part of the members 19. Alternatively it may be supported by its back resting on the top edge of the rear wall 30 of the members 19, as shown in broken lines in Figure 3, or hinged supporting arms (not shown) may be provided so that the rest can be arranged at any position along the guides 18.

The ledge 21 is provided with a strip light by 35 which the music is illuminated when the panel is turned into its music rest position.

In a structure such as is above described, the panel or music rack structure, when in the closed position, has one face thereof in the plane of the 40 adjacent portions of the top of the piano. The position of the panel, so that it may be used as a rack for supporting sheet music, is such that the music does not contact with the face of the panel which is exposed when it is in the closed 45 position.

In opening and closing the rack, the panel has a combined pivoting and sliding movement. The grooves or guides 18 permit this combined sliding and turning movement, the pins or sliders 17 being so positioned in relation to the one edge of the panel as to be spaced therefrom to an extent to permit the rack to be supported in a desired inclined position by engagement of the edge portion of the rack projecting beyond the pivots with the bottom edge of the opening in the piano top,

as clearly shown in Fig. 3 of the drawing, when the rack is positioned toward the edge of the opening nearest the keyboard. If desired, as shown in dotted lines in this figure, the top of the rack may be rested against the edge of the opening most remote from the keyboard.

Irrespective of the position of the panel when in the open position, when the panel is closed the music rest 21 will be concealed within the top, thus providing a flush top surface. The provision of a notch 20, as the panel is closed, permits one edge thereof to be positioned adjacent the ledge 21, and the panel to have sufficient rise to bring the top thereof flush with the top of the piano.

What I claim and desire to secure by Letters Patent is:

1. A piano embodying therein a case, provided with an opening in the top thereof adjacent the keyboard, a panel of a width to pass through said opening and, when in one position, to close same, pivotal supporting means for said panel at the opposite edges thereof and co-operating with the side walls of said opening, and an extension upon said panel beyond said supporting means adapted to engage the under side of the piano top, whereby said panel may be removed from said opening and brought to an upwardly and rearwardly inclined position away from said keyboard.

2. A piano embodying therein a case, provided with an opening in the top thereof adjacent the keyboard, guides within the opposite side edges

of said opening, a panel adapted to close said opening, pivots upon opposite edges of said panel rotatably and slidably mounted in said guides, and a ledge upon one face of said panel adjacent 5 said pivots but spaced from the edge of the panel, said ledge forming both an abutment to position said panel at the desired angle and a support for music, said panel having combined sliding and 10 turning movement, and a portion thereof adjacent said ledge, by engagement with the laterally extending edges of the opening, operating in conjunction with the slidable pivots to support said panel in operative position.

3. A piano embodying therein a case, provided 15 with an opening in the top thereof adjacent the keyboard, guides within the opposite side edges of said opening, a panel adapted to close said opening, pivots upon opposite edges of said panel rotatably and slidably mounted in said guides, 20 notches in the underside of the piano top in which said pivots register when the panel is in closed position, and a ledge upon one face of said panel adjacent said pivots but spaced from the edge of the panel, said ledge forming both an 25 abutment to position said panel at the desired angle of support and a ledge for the support of the music, said panel having combined sliding and turning movement, and a portion thereof, adjacent said ledge, by engagement with the laterally 30 extending edges of the opening, operating in conjunction with the slidable pivots to support said panel in operative position.

SAMUEL TRUDE FRIPP.
